Claims priority, application Canada Nov. 16, 1953

7 Claims. (Cl. 214—6)

This invention relates to machines for assembling articles from a conveyer line into a unit load which may be handled by a fork truck. In the embodiment herein described and illustrated, articles from the conveyer line are assembled onto pallets with tiers of articles assembled in patterns providing interlocking between the tiers, and the loaded pallets are discharged into position for removal by a fork truck.

In ordinary material handling installations, articles moving along a conveyer line, as from a production line, are manually assembled onto pallets or other unit loads which may be handled by a fork truck for warehousing and shipping purposes. While there have been proposals for automatically assembling articles from a conveyer onto a pallet, these proposals have for the most part been limited to the handling of articles of a specific size or shape and difficulties have been encountered when efforts have been made to utilize such machines on articles of a different size or shape. Also machine loaded pallets have frequently carried unstable loads due to the inability of machines to compact the articles as they are loaded on the pallet. Such machines have been of inefficient design and required repeated handling of articles from the time they leave the conveyer until they are positioned properly upon the pallet.

A major object of this invention is to provide a machine adaptable to assemble articles of varying sizes and shapes into a stable unit load.

An important object of the invention is to assemble a layer of articles by feeding successive rows from a conveyer directly onto an apron from which the layer may be deposited upon the pallet.

Another object of the invention is to provide a pallet loading machine of compact design which occupies a minimum of floor space and therefore has a large capacity per unit of area.

Still another object of the invention is to provide a pallet loading machine in which each layer of articles is compacted as it is deposited upon the pallet to increase the stability of the load on the pallet.

A specific object of this invention is to provide an article turning device which satisfactorily turns or otherwise handles cartons in pairs as well as individually in order that such cartons may be stacked at an increased rate in desired patterns upon a pallet.

Another specific object of the invention is to provide an improved control by which the lift supporting the pallet is lowered following deposit of a layer of articles upon the pallet until the upper surface of the deposited layer is positioned a specific distance beneath the apron from which the load is deposited.

In the attainment of these objects, one important feature of the invention resides in the arrangement of an apron at the upper part of a shaft in which the pallet is raised and lowered with a conveyer extending from the upper part of the shaft to feed articles directly onto selected areas of the apron which are successively positioned in alignment with the conveyer. At the back of the shaft is an empty pallet magazine for receiving and containing

2

a stack of empty pallets which are shifted one by one by a transfer device to the bottom of the shaft where a lift raises the pallet to a point beneath the apron. The apron is shiftable from its extended position overlying a pallet on the lift to a retracted position withdrawn from the shaft and positioned overtop of the empty pallet magazine. Extending from the front of the shaft and aligned with the transfer for the pallet is a pallet discharge conveyer which removes a loaded pallet from the lift and moves the loaded pallet to a position for loading onto a forked truck.

Cooperating with the feeding conveyer is a suitable escapement for controlling the feed of articles and, in cases of loading the articles in pairs, assuring the presence of a pair of articles at the infeed conveyor. Then, an article or a pair of articles is moved by the conveyer past a turning device which is selectively operated to permit the articles to continue or to turn them through an angle of 90°. Then, the articles are assembled in a row from which they are transferred by the feeding conveyer and the transfer device onto the apron which is indexed to receive successive rows until a layer is completed, at which time the apron is withdrawn and the layer deposited upon the pallet on the lift. Raising and lowering of the lift is controlled by a device at the upper part of the shaft and preferably beneath the apron which is retracted by the apron to initiate lowering of the lift until the upper surface of the articles on the lift passes beneath the device whereupon lowering of the lift is arrested. To accomplish the turning of an article or a pair of articles, the turning device includes a pair of pivotally mounted arms with independent power devices for swinging one of the arms to an article engaging position across the conveyer and then swinging both arms as a unit in the direction of travel of the conveyer to turn the article as it is moved along the conveyer path as well as to return the arms to a position paralleling the conveyer and retracted from the path of the article. Control of the full pallet lift is effected by a control unit which has an arm swingable beneath the apron to a position above the lift and retractable by the apron to initiate lowering of the lift. A finger is movable on the end of the arm to engage the surface of articles on the lift and control movement of the lift.

Other objects, features and advantages of the invention will become apparent from the following specification taken in conjunction with the accompanying drawings wherein:

General arrangement

In the machine shown in the drawings, a supply of empty pallets P may be stored in a compartment 50 forming an empty pallet magazine. At the bottom of the empty pallet magazine is a chain conveyer 51 arranged to receive the lowermost pallet and transfer it onto a lift platform 53 adapted to rise and lower in a well or shaft 54 adjacent the magazine. Platform 53 is raised to a position to present the empty pallet carried thereby under and close to the plane of a horizontally movable apron 55 adapted to receive a layer of articles, such as cartons C, which has been formed into a desired pattern on the apron; the platform is lowered in increments as it receives successive layers of articles. When a predetermined load of superimposed layers of articles have been deposited on the pallet to assemble or form a unit load, the platform lowers to deposit the loaded pallet upon a discharge chain conveyer 56 by which it is moved onto a roller conveyer platform 57 for disposal.

The cartons or other articles to be formed into a unit load are brought to the machine by a conveyer such as gravity conveyer 57 and moved on a feeding conveyer in the form of an endless belt conveyer 58 extending from the shaft 54 in a direction normal to the direction of movement of the apron 55.

An escapement 59 is disposed in the path of the conveyer 58, adjacent its receive end, adapted to control the movement on the belt toward the apron; the escapement is normally in a position to stop a carton entering the machine. Beyond the escapement is a carton-turning device 60 controlled to turn cartons individually or in pairs through an angle of 90° on the belt, or to allow cartons to be moved by the belt onto the apron without turning to form cartons in a desired pattern on the apron. Beyond the turning device 60 is a build-up area which is in part defined on one side by the frame of the conveyer 58, on the other side by a guide 62, which is preferably spring-loaded, and at its end by a normally-raised carton stop 63.

Carton stop 63 remains in raised position, arresting the movement of a number of aligned cartons (the upper run of the belt sliding under the cartons) until the required number of cartons have been assembled ready to be transferred as a unit onto the apron. As the last of the number of cartons to be transferred as a unit engages the immediately preceding carton, the carton stop lowers, and a pusher element 67 of a transfer device 68 engages

the last carton to assist the transfer of the row of articles onto the apron against a selected carton locator stop 69. Before the carton stop 63 is lowered, the apron 55 is indexed from its retracted position over the empty pallet magazine over the shaft 54 and resting on the lift platform a distance sufficient to provide a supporting surface for the row of cartons to be transferred onto the apron. When cartons have been assembled in the build-up area to form another row, the apron 55 again is indexed an increment sufficient to receive the next row of cartons and the pusher 67 comes into operation to assist the transfer of the second row onto the apron.

When the last row to complete the layer is assembled on the apron, the apron is retracted, allowing the layer 15 cartons to drop onto the pallet. Closing in guides 70 and 71 at the top of the shaft are operated to press inwardly on the end and both sides of the layer to compact the cartons in the layer as they drop onto the pallet. Platform 53 is lowered to the extent of the depth or 20 height of the cartons, finally coming to a stop with the tops of the cartons immediately below the apron ready to receive a second layer or pattern of cartons.

The second layer of cartons, formed on the apron in a predetermined pattern, as previously explained, is deposited upon the first layer (resting on the platform); 25 and so on, until the pallet is fully loaded, following which the loaded platform 53 lowers and deposits the loaded pallet onto the discharge conveyer 56. As the loaded pallet moves off the platform 53, an empty pallet is conveyed from the magazine 50 onto the now empty platform, and the platform rises and comes to a stop, ready to receive a layer of articles from the apron 55.

Carton entry escapement

35 The escapement 59 controlling entry of cartons to the machine on feeding conveyer 58 includes a roller 72 (Fig. 7) journaled in the ends of a pair of arms 73 fixed to a shaft 74 journaled in the frame 75 of the endless belt conveyer 53.

40 A conventional three-pulley device is used to impart a downwardly-directed half loop 76 to the upper run of the belt of the belt conveyer, so that, in effect, the loop defines a recess. The recess serves to accommodate the escapement roller 72 when the roller is in its inoperative position, that is when the arms 73 are in substantially horizontal position and the periphery of the roller lies in the plane of the upper face of the upper run of the conveyer belt so that the roller does not impede the movement of any carton being moved forwardly by the belt.

50 The escapement roller is adapted to be bodily rotated in an arc of approximately 90° by rotating the shaft 74 through 90°, in effect, to rise above the plane of the upper run of the belt and present an abutment to any oncoming carton, by which the carton is stopped.

55 Preferably, some of the rollers 77 supporting the belt conveyor have adjustably mounted shafts 78 to train the belt 58 as desired.

60 Fixed to one end of the shaft 74 is an arm 79 pivotally connected to piston rod 80 of an air cylinder 81. The end of the cylinder remote from the piston is pivotally supported as at 82 on a suitable bracket 83 secured to the conveyor frame.

65 The opposite (head and rear) ends of the cylinder 81 are operatively connected by conduits to a solenoid-operated spring offset 4-way conventional air valve V-1 (Fig. 20) which controls the admission of air under pressure into the head or the rear end of the cylinder accordingly to actuate the piston in one or the other direction. The 70 arrangement is such that the escapement roller 72 is normally in raised carton-stopping position when the valve V-1 is de-energized. Fixed to the shaft 74 is a striker arm 86 (Fig. 2) which is adapted to operate two limit switches LS-9 and LS-7 mounted on the frame.

75 Mounted on the side frame of the belt conveyor 58 at

the infeed end are two normally open limit switches LS-1 and LS-2 (Fig. 1). Positioned adjacent limit switches LS-1 is a spring-loaded, switch-operating cam 88 having a strike arm 89 operable by a carton as it reaches the escapement roller 72. A similar switch operating cam 90 and striker 91 assembly is mounted adjacent limit switch LS-2. Arms 89 and 91 normally extend transversely of the belt conveyor to be engaged by a carton entering the mechanism.

If large cartons are being fed into the machine, both such arms will be engaged by the same carton. If pairs of cartons are being handled, the two arms will be engaged separately by the two cartons.

Upon operation of striker arms 89 and 91, the cams 88 and 90 operate the limit switches LS-1 and LS-2 to close the switches and hold them closed during the passage of the carton and while the striker is engaged by the carton.

When the two normally-open limit switches LS-1 and LS-2, which are in series, are closed, whether by a single large carton or by a pair of cartons, the solenoid-operated air valve V-1 is energized, to allow air under pressure to enter the head end of the cylinder to rotate the escapement roller downwardly below the plane of the upper run of the belt conveyor, out of the path of the carton. As the carton moves forwardly under the action of the belt, it engages striker arm 92 of a normally-open limit switch LS-3 which is operated to closed position by a cam 93 similar in construction to the carton-operated cam previously described. This limit switch LS-3, when closed by a carton and while the carton still holds the switches LS-1 and LS-2 closed, actuates a relay to deenergize solenoid-operated air valve V-1 so that the valve is spring-returned to its normal position when air under pressure is admitted into the rear end of the cylinder to move the plunger to raise the escapement roller to its normal, carton-stopping position. The switch LS-3 is so positioned that it is actuated while the trailing end of the entering carton is over the escapement roller 92 and raised by the roller, but the carton is moved forwardly by the action of the belt and partly pushed by the following carton, if any. As the carton moves off the escapement roller, the following carton, if any, comes to a stop against the escapement roller.

Carton turning device

As already stated, this carton turning device 60 serves, when actuated, to turn a carton, or a pair of cartons through an angle of ninety degrees.

Two arms 96 and 97 are rotatable on a common vertical axis, so that they both rotate in a horizontal plane. The arms, when in initial or normal position, are directed lengthwise and clear of the conveyor belt, being enclosed in a housing 98. The arms conveniently are of channel cross section, and of different depth. One arm, 96, is formed with two spaced hubs 99, 99 (Fig. 11) supported on a boss 100 supported by the lower wall or plate 101 of the housing 98 and rotating on a vertical shaft 102. The other arm, 97, is attached to a hub 103 turning on the shaft between the two hubs 99.

A lug or abutment 104 is formed on the hubs 99 of the arm 96; an abutment 105 is formed on the hub 103 of the arm 97. The abutments 104 and 105 are so disposed that they engage each other when the arms are in the relative positions shown in Figure 10, that is, when the arm 96 is in its operative position and the arm 97 is in its initial position. While such engagement is maintained, the arm 97 cannot rotate clockwise (as seen in Figure 10) without rotating the arm 96 therewith.

The arm 96 is rotated counter-clockwise substantially 90° to operative position and returned to its normal position, by a two-way air cylinder 106 having its piston rod 107 pivotally connected at 103 to the arm 97. The other arm 97 is likewise rotated approximately 90°, clockwise from a normal position by an air cylinder 109, having its piston rod 110 pivotally connected at 111 to the arm 97.

Both of the air cylinders are mounted in a bracket 112 for oscillatory displacement on vertical axes.

Pivotedly mounted within the arm 96 as at 114, to rotate on a vertical axis, is a finger 115. The finger is retained in a normal position by a spring 116 tensioned between an adjustable screw 117 carried by the free end of the arm 96 and an extremity of the finger 115, the normal position being determined by the engagement of a portion of the finger with the web of the channel arm. 10 One end of the finger is formed with a portion which extends through an aperture in the web of the arm and is formed to present a portion 118 which lies at an obtuse angle to the plane of the forward face or web of the arm so that, when the arm is in its operative position, transversely of the belt, the portion 118 is presented tangentially to an oncoming carton. As the carton moves forwardly with the belt, it engages the portion 118, and rotates the finger clockwise on its axis against the tension in the spring 116. The carton advances until its leading 20 face engages the arm 96. In this position, the carton is pressing against the arm because of the action of the belt, and the carton is restrained against lateral displacement by the finger portion 118 and the conveyor guard rail.

Air to actuate the two air cylinders 106 and 109 is 25 controlled by a 2-position 4-way momentary contact solenoid-operated air valve V-2 (Fig. 23). The cylinders are so piped to the air valve V-2 and to a cam-operated air valve 121, that when striker 120 on the arm 96 engages the cam-operated air valve, air pressure is applied to the 30 head end of the cylinder 109 to shift the arm 97 to its normal position and to retain it in that position.

When control circuits are actuated to effect carton turning, in manner to be described, solenoid valve V-2 is 35 shifted so air enters the rear end of the air cylinder 106, causing it to stroke out and rotate the arm 96 counter-clockwise as viewed in Figure 10 to its operated position, in the path of oncoming cartons. As the arm 96 rotates, it releases the cam-operated air valve 121, to reverse the 40 port connections to the cylinder 109. The cylinder 109, however, does not operate to rotate the arm 97 clockwise since the entering air line to the cam-operated valve 121 is now effectively connected to the exhaust line through the valve V-2. However, as a carton reaches the turning 45 devices it actuates normally-open limit switch LS-8 on top of housing 98 by engagement with striker 119, so the "in" solenoid of the valve V-2 is energized, causing the valve V-2 to reverse. Air will now flow from the valve V-2, through the cam-operated valve 121, and into the 50 rear of the cylinder 109, causing it to stroke out; at the same time, air flows into the head end of the cylinder 106. Both arms now rotate together in a clockwise direction 55 90° apart. This 90° relationship is maintained by slightly retarding the rate of (clockwise) rotation of the arm 96 by the use of a speed control valve 123, so that the abutments 104 and 105 on the arms are in contact.

As the (clockwise) rotation of both arms proceeds, the front face of the carton contacts a tapered portion 124 of the housing 98 so the rotational movement of the carton is arrested. Continued rotation of the arm 96, and its ingress through a slot into the housing 98, strips the gripper finger from the carton, so that the carton is now free to move with the belt, the carton having been turned 90°. As the arm 96 reaches its normal position, striker 120 60 engages the air valve 121, reversing the valve and allowing air to enter the head end of the cylinder 109, causing it to stroke in. This imparts a counter-clockwise rotation to the arm 97, causing it to return to its normal or at rest position. A speed control valve 125 is used to retard the return of the arm 97 to its initial position.

70 Either a single carton or a pair of smaller cartons may proceed straight past the turning device 60 to be transferred to the apron in their original orientation, or, upon actuation of electrical controls to be described, may be turned as a unit through an angle of 90° without interruption to their movement along the belt 58. In this way, the

orientation of cartons in the pattern to be assembled on the apron may be varied according to the size and shape of the cartons as well as the desired arrangement on the pallet. If the electrical controls signal the turning of an incoming carton as it leaves the escapement 59, the arm 96 is shifted to its operative position and the incoming carton engages striker 119 to actuate limit switch LS-8 as the leading edge of the carton engages arm 96 and is retained by finger 115. This causes operation, in opposite directions, of the cylinders 106 and 109 to rotate the arms 97 and 96 as a unit in a clockwise direction thereby turning either a single carton or a pair of cartons together through an angle of 90° until the cartons are removed by engagement with tapered portion 124 of the housing 98 whereupon the cartons are released and continue along with the belt 58. Arm 96, upon actuating valve 121 causes return of arm 97 to its inoperative and retracted position.

Transfer mechanism

The transfer device 68 is used to assist in the transfer of a row of cartons, that is, a predetermined number of cartons assembled in the pattern build-up area, immediately at and stopped by the stop 63, as a unit onto the apron 55. This device essentially consists of pusher element 67 which is normally held at rest and in a horizontal position out of the path of any carton travelling on the belt toward the build-up area, and which, upon the lowering of the stop 63, lowers to a vertical position and bodily moves forwardly to overtake the last of the cartons of the row to be transferred and to push the row onto the apron, following which the pusher returns to its initial location and to its normally-horizontal position.

The pusher element 67 forms one arm of a lever 127 (Figs. 6 and 12) pivotally mounted on a shaft 129 in a carriage 128 movable in tracks such as 130 formed in a frame structure 131 supported by suitable supports 132 above the plane of the belt 58 and overlying the same.

The carriage 128 is reciprocated by reciprocation of a hydraulically-operated cylinder 133 fixed to the frame structure. To provide for the required longitudinal displacement of the carriage 128 by a cylinder of a given stroke, the carriage is so operatively connected to the piston rod 134 of the cylinder that the stroke or displacement of the carriage is more than that of the piston rod in the ratio of 2 to 1 in the present instance. For that purpose, the piston rod has its outer end connected to a carriage 135 in the form of a rectangular frame riding in grooved tracks such as 136 formed on the inside faces of the side members of the frame structure 131.

Freely journalled in the carriage 135 are two sprockets 137 and 138. Freely journalled in the frame structure, adjacent the opposite ends thereof, are two sprockets 139 and 140. A chain 141, having its opposite ends anchored to the frame structure and to one end of the carriage, is passed around the sprockets 137 and 139. Another chain 142, having its opposite ends anchored to the frame and to the other end of the carriage, is passed around sprockets 138 and 140.

Journalled on the shaft 129 are a pair of lever arms such as 144 on the ends of which are freely journalled cam rollers such as 145 adapted to ride in one or the other of two cam tracks 146 and 147 formed on the inside faces of the side members of the frame structure 131. Fingers such as 148 pivoted at their lower ends to the side members of the frame structure and spring-loaded normally to lie in a vertical direction to close the rearward ends of the upper cam tracks serve as stops for the lever cam rollers as the carriage 128 is moved forwardly. The fingers, on the other hand, are free to rotate counter-clockwise, as viewed in Figure 12, to allow the lever cam rollers 145 to ride out of the cam tracks 146, when, as will be presently explained, the carriage is returned from the end of its carton-pushing stroke to its normal starting position shown in Figure 12. Fingers such as 149 pivoted at their upper ends to the side members of the frame structure are

spring-loaded normally to close the lower cam tracks adjacent their forward extremities. The fingers rotate counter-clockwise to permit the passage of the lever cam rollers as the carriage is moved forwardly on its carton-pushing stroke, but serve as ramps guiding the lever rollers from the lower roller cam tracks to the upper cam tracks as the carriage is drawn rearwardly toward its initial position. Thus, as the carriage 128 is drawn forwardly, the lever rollers engage the finger 149 and cause the carton-engaging arm 127 to lower to a substantially vertical position rearwardly of the last carton in the row to be transferred onto the apron. Irrespective of the relative lineal speed of the belt and the arm, the arm catches up with the last carton as the row loses speed as the cartons leave the belt and slide over the apron as illustrated in Fig. 6.

The effective stroke of the arm is such that the row will be fully resting upon the apron, in engagement with the carton locator 69 before the arm reverses its forward stroke to return to its initial position.

20 The hydraulically-operated cylinder 133 is controlled by a two-position, 4-way spring offset solenoid-operated hydraulic valve V-4 (shown diagrammatically only in Figure 21). In the normal position of the valve, hydraulic fluid is admitted into the rear end of the cylinder 25 so that the cylinder rod 134 is in its outward position and the pusher arm is in its initial position as shown in Fig. 12.

Carton stop

Between the pattern build-up area beneath the transfer 30 mechanism and the apron, the carton stop 63 defines the extreme end of the build-up area, at the inner end of the belt conveyer. The stop is used to hold the cartons in the area on the belt, which slides under the cartons, until the required number of cartons are in place ready to 35 be transferred as a row unit onto the apron.

The stop 63 includes a spring-loaded stop plate 170 mounted for vertical movement, between a normally-raised position which arrests the forward movement of the 40 carton in engagement therewith, and a lowered position substantially flush with the plane of the upper run of the belt conveyer.

The cartons in the build-up area are transferred onto the apron 55 upon the lowering of the stop. As seen in Figure 12, a plate 170 has fixed thereto a number of 45 rods such as 171 which are slidable in flange 172 on a plate 173. The rods are threaded on their free ends to receive nuts such as 174. Compressed between the plates 170 and 173 are coiled springs such as 175 (Fig. 12). The arrangement serves as a buffer to cushion the impact 50 articles engaging the stop as well as the impact of accumulated articles.

The plate 173 carries a number of vertically directed rods such as 176 sliding in brackets like 177 secured to a frame member 178.

55 The stop device is actuated vertically by an air cylinder 181 controlled by a spring offset solenoid-operated 4-way valve V-3 (Figure 21) piped so that the stop is normally in raised, carton-stopping position as aforesaid with the solenoid valve V-3 de-energized.

When the solenoid of the valve is energized, the valve is actuated to reverse the flow of air to the cylinder, causing the stop to lower, and thus allowing the transfer of the row of cartons onto the apron. After the row has been transferred onto the apron, the solenoid is de-energized, allowing the air valve to reset under the action of its spring, thus again causing the reversal of the flow of air to the cylinder and causing the stop to rise to its normal raised position.

Empty pallet magazine and lift

70 As already stated, in the empty pallet magazine 50 are stacked a number of pallets P, and such pallets are dropped successively (singly) onto the conveyer 51. The magazine is in part defined by a bulkhead 182 (Figure 4) formed with an opening 183 providing a passage for a

pallet as it is being transferred to the full pallet lift platform 53 by the chains of the conveyer. A front plate 184 serves to conceal the lifting mechanism.

A lift platform 185 disposed in the bottom of the magazine is raised and lowered by a pneumatically-operated toggle mechanism to raise the entire stack of pallets and subsequently deposit the lowermost pallet onto the conveyer, while the remainder of the stack is supported above and clear of the lowermost pallet.

An air cylinder 186 is pivotally supported as at 187 by brackets 188. The piston rod is pivotally connected as at 189 to an arm 190 rigid to a shaft 191 journalled in brackets 192. Another shaft 193 is journalled in brackets similar to brackets 192. Both shafts are rotated or oscillated together as by a link 194 pivotally connected at its opposite ends to levers 195 rigid on the shafts 193 and 191.

Rigid with the shafts are levers 196 the outer ends of which are pivotally connected to the lower ends of links 197 as at 198; the upper ends of the links are pivotally connected to the frame of the lift. Opposite sides of the lift frame carry freely rotatable wheels 199 which ride in vertically-directed tracks 200. The lift platform is thus constrained to a vertical movement. As the cylinder 186 strokes out, the platform rises, the platform lowering as the cylinder strokes in.

Rotatably supported on two sides of the lift are two shafts 201 to which are rigidly secured members 202 having fingers 203 adapted to be inserted into the framework of a pallet to form supports therefor. Also fixed to the shafts 201 are cam levers 204 spring-loaded as by springs 205 to urge rotation of the shafts in opposite direction to withdraw the supporting fingers 203 from the pallet and to release the same.

Suspended from the frame of the lift are members 206 each carrying a cam follower 207 engaging the cam face 208 on cams 204 to control the angular position of the shaft 201 to which it is fixed and therefore, the position of the fingers 203.

The cams are such that when the platform is in its lowered position, the fingers are in their operative pallet-supporting position. As the platform rises, the cams, being spring-loaded, tend to withdraw the fingers to inoperative position. If a pallet is supported by the fingers the tension in the spring 205 is not sufficient to withdraw the fingers because of the load imposed by the stack of pallets. As the platform rises farther, it lifts the pallet off the fingers and the fingers withdraw fully out of the path of the pallet. As the platform begins to lower, it lowers the pallet therewith, and when the pallet is below the fingers, the rollers 207 actuate the fingers inwardly inserting them into the pallet lying above the pallet immediately in contact with the platform. As the platform continues its lowering movement, the fingers provide supports for the stack of pallets which lie above the pallet being lowered by the platform. The air cylinder is controlled by a momentary contact 2-position solenoid operated 4-way air valve V-5. Fixed to the shaft 191 are two actuators adapted to operate, respectively, two limit switches LS-14 and LS-15. The switch LS-14 is a normally-open switch which is closed when the air cylinder is in its "in" position, that is, when the lift is in its fully lowered position. Switch LS-15 is a normally-open switch and is closed when the air-cylinder is in its fully "out" position, that is, when the lift is in its fully raised position.

Positioned adjacent the bulkhead 182 is a limit switch LS-13. This switch is actuated by a pallet lying on the conveyor, and remains actuated until the pallet has been moved through the bulkhead onto the full-pallet platform 53.

Full pallet lift

Full pallet lift 53 receives an empty pallet from the empty pallet magazine and elevates the pallet to present the same just below the plane of travel of the apron 55.

The lift is lowered in successive steps as layers of cartons are dropped from the apron, and is finally lowered to deposit the loaded pallet onto the discharge conveyer.

The lift platform 53 includes a channel beam 209 (Figs. 4 and 6) supporting a number of cross channels 210 in which rollers 211 are freely rotatable. The ends of the beam 209 have shoes 212 which slide in vertical tracks 213 so that the platform rises and lowers.

The platform is suspended by hoisting chains 215, 10 215, and raised and lowered by the operation of a hydraulic cylinder 214. The operation of the cylinder is controlled by a 4-way spring-centered solenoid-operated hydraulic valve V-6 (Fig. 22).

One chain is anchored at one end to one end of the 15 beam, more particularly to one of the shoes 212 and passed over three sprockets 216 and attached at its other end to a coupler 217. The other chain is anchored at one end to the other shoe on the beam and passes over sprocket 218 and attached to the coupler 217. The coupler in turn is attached to one end of a chain 220 which passes around a sprocket 221 freely rotatably mounted to the end of piston rod 219 of the hydraulic cylinder 214 and is anchored at its other end to a bracket 222 secured to the machine frame. The 25 platform therefore is raised as the cylinder strokes up and lowered as the cylinder strokes down, the lift platform 53 rising or lowering twice the displacement of the piston rod 219.

The upper end of the piston rod 219 is secured to 30 carriage 225, in which the sprocket 221 is journalled, which rides in tracks 227. Carried by the carriage is a striker 226 adapted to engage three normally-open limit switches LS-21, LS-18 and LS-17 mounted on one of the tracks 227 to control operation of the lift in a manner 35 to be described. A spring loaded arm 228 carries a roller resting on the chain 220 to open a normally-closed limit switch LS-27 should the chain become slack as a result of the platform jamming on its downward movement.

40

Apron

Apron 55 is in the form of a plate adapted to be moved from a retracted position above the empty pallet magazine 50 to a position at the top of shaft 54 to overlie the pallet resting upon the lift platform 53.

45 Apron 55 is indexed in increments or steps to receive successive rows of cartons transferred from the build-up area. When the apron has received its full pattern load, it withdraws over the empty pallet magazine, beneath a stripper beam 229 positioned above the path of travel of the apron, at the adjacent end of the magazine, serving to slide the layer of cartons off the apron onto the pallet.

50 Wheels 230 (Fig. 6) mounted to angle irons 231 secured to the underside of the apron ride in tracks 232 carried at the top of the machine frame and extend over the shaft 54 as well as empty pallet magazine 50.

55 Apron 55 is actuated by chains 233 (Fig. 5) attached at opposite ends to the apron and passed around sprockets 234 fixed to parallel horizontal shafts 235 and 236.

60 Shaft 236 has an extension keyed to a sprocket 237 of a diameter smaller than that of the sprockets 234. A bracket 238 on the machine frame supports a hydraulic cylinder 239 having its piston rod coupled to a carriage 240 which rides in tracks 241. Attached at its opposite ends to the carriage is a chain 242 passed around the sprocket 237 and around a sprocket 243 journalled in a chain tensioning device 244. As the rod strokes out or strokes in, the apron is reciprocated, moving in the tracks 242. As the diameter of the sprocket 237 is (in the present instance) one half of the diameter of the sprocket 234, the apron moves twice the distance of the stroke of the cylinder rod. The arrangement is such that when the apron lies in its normal position, above the empty pallet magazine, the cylinder rod is fully out. Thus, as

the rod moves in, the apron strokes out, to receive a row of cartons from the build-up area.

Slidably supported near the outer end of apron tracks 232 is a bumper 247 which is normally urged inwardly as by springs 247a. At its bottom, bumper 247 has a flange 247b arranged to be engaged by the leading edge of the apron on its out stroke. When the apron is withdrawn, springs 247a move bumper 247 inwardly to straighten any cartons which tend to tip over.

Hydraulic cylinder 239 is controlled by a 4-way spring centered solenoid operated hydraulic valve V-7 (Fig. 21). Attached to the carriage 240 is a limit switch actuator 240a which actuates limit switches LS-11, LS-11a, LS-11b, LS-11c and LS-10.

Fixed to the underside of the apron is a striker 245 positioned adjacent the leading edge of the apron, and adapted to actuate full pallet lift control 246.

Full pallet lift control

As already stated, the full pallet lift platform 53 moves vertically between a lowered, loaded pallet discharge position (or empty pallet receiving position) to a raised position under the path of the apron 55, to receive from the apron a layer or pattern of cartons as the apron withdraws over the empty pallet magazine. The operation of the lift platform is controlled primarily by the full pallet lift control 246 aforesaid, during the period that the several layers of load are being assembled on the platform.

The control comprises an arm 248 (Figs. 13 and 14) having a hub 249 rotatable on a fixed shaft 250 supported in a bracket 251 carried by a member 252 of the machine frame positioned to lie below the plane of travel of the apron 55. Journalled in a bearing 254 carried by the bracket 248 is a shaft 255 to one end of which are secured a pair of fingers 256 carrying a finger roller 257.

The arm 248 is urged in a clockwise rotation by a conventional spring loaded dash pot 258, operatively connected to the arm by a link-rod 260. The clockwise rotation of the arm is limited by the engagement of an abutment 261 on the hub 249 with a screw 262 carried by an angle 263 secured to the bracket 25. The extended position of the arm 248 is such that the finger roller 257 overlies the lift platform. The arm is rotated counter-clockwise by the striker 245 as the apron moves on its withdrawing stroke to drop the layer of cartons on the apron onto the pallet.

The roller 257 of the finger is held in a predetermined normal position, more or less horizontal, by a lug 264 rotating with the shaft 255 and engaging a screw 265 adjustably carried by the bracket 248. Also rotating with the shaft 255 is a cam 266 adapted to open a normally-closed limit switch LS-25 when the finger 257 is rotated or raised by a pallet or a carton lying on a pallet in the shaft.

Journalled on the shaft 250 is a collar 267a carrying a cam lever 267, and urged in a counter-clockwise direction by a spring 268 tensioned between a lug 269 on the collar 267a the bracket 251. The upper end of the hub 249 is formed with an arcuate projection 270 which is received in an arcuate recess 271 formed in the lower edge of the hub 267a. The arcuate length of the recess 271 is greater than that of the projection 270 in effect providing a lost-motion clutch. The tension in the spring 268 retains the leading edge of the projection in engagement with one end of the recess 271 as the arm is urged clockwise during retraction of the apron. The lever 267 is however free to rotate clockwise relatively to the bracket 248 until trailing edge of the projection engages with the opposite end of the recess. The lever 267 is actuated by the striker 245 secured to the underside of the apron and is positioned to engage a roller 272 carried by the end of the lever 267. The striker is also positioned a short distance from the leading edge of the apron, so that the

lever 267 will be engaged shortly before the apron reaches its full retracted position.

Fixed to the hub 249 is a limit switch striker 273 adapted to close the normally-open contacts and open the normally-closed contacts of a limit switch LS-26 as the arm rotates counter-clockwise upon retraction of the apron 55.

Normally, the arm 248 is disposed in the position shown in Fig. 13 with the finger roller 257 disposed within the shaft above cartons on the pallet. As the apron retracts and approaches its retracted position, striker 245 engages roller 272 on lever 267 turning collar 267a counter-clockwise about the shaft 250. The end of the recess 271 in the collar engages the end of projection 270 on the hub 249 to rotate the hub also in a counter-clockwise direction and turn the arm 248 counter-clockwise about the shaft 250 thereby retracting the finger roller 257 to a position withdrawn from the shaft and free of the pallet and cartons on the full pallet lift. At this stage, the 20 layer of cartons is deposited on the lift and actuation of limit switch LS-26 by the striker 273 initiates lowering movement of the lift. After the striker 245 on the spron 55 has passed the roller 272, the lever 267 as well as arm 248 are released to the action of the spring-loaded dash 25 pot 258 causing the arm 248 to turn in a clockwise direction about the shaft 250. This clockwise movement is arrested upon engagement of the finger roller 257 with the side of a carton on the pull pallet lift so the lift continues to lower until the finger 257 passes over the top 30 surface of the uppermost layer of cartons and releases limit switch 226 with the arm 248 and finger roller 257 extended into the shaft. Then, the direction of movement of the full pallet lift is reversed so the lift is raised and raises the top surface of the uppermost layer of cartons 35 into engagement with finger roller 257. Turning of finger roller 257 and shaft 255 actuates striker 266 and limit switch LS-25 to stop movement of the lift with the upper surface of the cartons disposed immediately beneath the apron. When the apron strokes forward to receive additional rows of cartons, striker 245 engages roller 272 and turns hub 267a about the shaft 250 against the action of spring 268, but by reason of the lost motion coupling between the hub 267a and the hub 249, the striker 245 passes the roller 272 without affecting the arm 248. 40 After the striker 245 has passed the roller 272, the spring 268 returns the roller 272 and its associated lever arm 267 to the position shown in Fig. 13 where retraction of the apron will initiate another cycle of operation of the full pallet lift control.

Carton locator stop

The carton locator stop is positioned above the apron on the side opposite the infeed end of the conveyer belt, and in alignment with the belt to be engaged by a line of 55 cartons transferred onto the apron by the pusher of the transfer mechanism. This locator stop serves two purposes: (1) to stop and selectively locate the end of the row of cartons transferred onto the apron, and, (2) to detect the end of the transfer operation.

As the completed pattern of cartons on the apron does not present, in plan, a square or rectangle because of the relative disposition of the cartons (some of the cartons are presented lengthwise across the apron and others transversely) the stop device is adapted to stop the rows in 60 two different positions.

For instance, if the pattern to be assembled or built up on the apron is that shown in Figure 1, the locator will operate to stop the outer rows at the same position, whereas the locator will operate to stop the other group 65 rearwardly of the first groups. The effective position of the device is selected by the counter circuit in a manner to be described.

The carton locator stop includes a carriage 274 (Figs. 15 and 16), in the form of a U, having side wheels 275 running in tracks carried by members 277 secured to the

frame structure. The carriage 274 is urged toward the apron (or toward the conveyer belt) by springs 278 tensioned between the carriage 274 and brackets on the members 277. The forward movement of the carriage is determined by the engagement of two of the front wheels 275 with abutments 280.

Fixed to the frame of the carriage 274, is an upright member 279 to which are secured a lower air cylinder 281 and an upper air cylinder 282. The rod of the upper cylinder is secured to a transverse plate or carton stop 283 (Fig. 6); likewise, the plunger of the lower cylinder is secured to a transverse plate or carton stop 284. The arrangement is such that one of the plates or stops, say the lower stop, will advance farther over the apron than the upper stop.

To the opposite ends of the stop plate 283 are rigidly secured rods 285 which are slidably supported in elongated bearings 286 carried by the frame of the carriage; likewise, rods rigidly secured to the lower plate 284 slide in similar elongated slide bearings carried by the frame of the carriage. The cylinders 281 and 282 are operated, selectively, by momentary-contact, 2-position solenoid operated 4-way air valves V-8 and V-9.

As a row of cartons is being transferred from the carton build-up area, the transfer circuit energizes the "out" solenoid of one or the other of the air valves V-8 or V-9, depending on whether the upper or the lower stop is to be advanced over the apron. When the lead carton of the row being transferred contacts the particular stop which has been actuated outwardly, it forces the carriage to move back against the tension of the springs 278. In moving back, a striker plate 287 fixed to the carriage engages and closes the normally-open limit switch LS-6 indicating the termination of the transfer operation.

Discharge and transfer conveyer chains

Pallets in the empty pallet magazine 50 are lowered one by one so the lowermost pallet rests upon beams 151 at the base of the empty pallet magazine. Extending from the beams 151, 151 beneath the partition 182 and into the shaft 54 are a pair of channels 152, 152 supporting the upper courses of endless drag chains 153, 153 which are operable to slide an empty pallet from the beams 151 onto the rollers 211 of the full pallet lift 53 when the lift is at the bottom of the shaft 54. Discharge chain 153 is guided and supported by sprockets 154, 154.

A pair of discharge chains 155, 155 extend from the lower part of the shaft in horizontal alignment with the chains 153, 153 outwardly to transfer a loaded pallet from the full pallet lift 53 onto the discharge conveyer 57. These discharge chains 155 are supported by sprockets 156, 156 and are driven by a chain 157 from a motor driven gear box 158. To synchronously drive the transfer chains 153, a connecting chain 159 extends from a sprocket on a shaft for the discharge chains 155 to a sprocket 160 for driving the transfer chains 153.

Supported by brackets 161 extending from one of the beams 151 is a rockshaft 162 to which are rigidly secured arms 163 carrying a control rod 164. Normally, control rod 164 is urged upwardly by a spring 165 which has one end anchored at 166 and the other end connected to a lever arm 167 on the shaft 162. Strikers 168 and 169 on the shaft 162 are arranged to actuate limit switches LS-13 and LS-16. Thus, the control bar 164 is depressed as an empty pallet is moved from the empty pallet magazine onto the full lift platform. When the pallet is properly positioned on the full lift platform, the control bar 164 is released and the spring returns the shaft 162 to its normal position thereby returning the limit switches LS-13 and LS-16 to their normal positions.

Closing-in guards

As already stated, when a layer of cartons has been deposited upon the pallet, guards 70 and 71 operate to press inwardly on three sides of the layer.

Two of the guards 71 are disposed longitudinally of the side edges of the apron; the third guard 70, is disposed adjacent to the end of the apron remote from the stripper beam 229.

- 5 Each of guards 71 is rigidly mounted on a shaft 290 (Fig. 18) journalled in bearings 291 supported by the machine structure. The guard 70 is pivotally mounted on a pair of brackets 292 supported by the machine structure. Separate air cylinders operate the three closing in guards. Guards 71, 71 are actuated by air cylinders 293, 293 and guard 70 is actuated by air cylinder 294. Air cylinder 293 has one end pivoted on a bracket 295 and its piston rod pivotally connected to an arm 296 rigidly secured to the shaft 290 so reciprocation of the piston and the cylinder 293 oscillates the closing in guards 71 from a retracted position as shown in full line in Fig. 18 to a position engaging the sides of cartons dropping onto the full pallet lift as illustrated in dotted lines in Fig. 18. Air cylinder 294 has its rear end pivotally connected to a bracket 297 on the machine frame and its piston rod pivoted directly to the closing in guard 70 as at 298 so reciprocation of the piston and cylinder 294 oscillates the closing in guard 70 about its pivotal connections to the bracket 292 from a retracted position as shown in full line in Fig. 19 to a carton engaging position as shown in dotted lines in that figure. All of the air cylinders 293 and 294 are controlled by a single spring offset two position solenoid operated air valve V-10 (Fig. 21). Air valve V-10 is so connected that it is actuated simultaneously with the actuation of air valve V-7 to effect the withdraw stroke of the apron 55.

The arrangement is such that normally, the guards are in their operative position as shown in dot and dash lines in Figs. 18 and 19. When the apron withdraws to drop the pattern onto the pallet, the solenoid of the air valve V-10 becomes energized, causing air to flow to the heads of the cylinders 293 and 294 and actuating the guards to their inoperative position, as shown in full lines. At the end of the withdraw stroke of the apron, the valve V-7, and the valve V-10, become de-energized, the valve V-10 shifts under the action of its spring, and the air cylinders 293 and 294 operate to actuate the guards to their operative position, thereby pushing in on the cartons.

Operation

In normal operation, when the machine is started, an empty pallet P is in position on the full pallet lift platform 53, with the pallet engaging sensing finger roller 257 on the full pallet lift control 246. A stack of empty pallets is supported on empty pallet support fingers 203 in the empty pallet magazine and one empty pallet is resting on the transfer chains 153 with the empty pallet lift platform 185 in its lowermost position.

While the machine may be adjusted to arrange the cartons in a variety of patterns, the operation of the machine will be described in the formation of different patterns in alternate layers of cartons, where pairs of cartons are assembled first with one row of eight cartons at one end of the pallet extending in one direction and then four rows of three cartons disposed normal to the cartons in the first row. The alternate pattern is similar except that the row of eight cartons is arranged at the opposite end of the pallet as shown in Figs. 1 and 17.

Air pressure is normally supplied through conduit 301 to escapement control valve V-1 which is urged by spring 302 to a position supplying air pressure through conduit 303 to the rear end of cylinder 81, thereby extending the piston rod 80 to project escapement roller 72 into the path of cartons moved by in-feed conveyer 76 toward the pallet loading machine. With this arrangement, a pair of cartons, which may not necessarily be transversely aligned, are moved by the in-feed conveyer 76 toward escapement roller 72 where they respectively engage operating arms 89 and 91 for limit switches LS-1 and LS-2. Assuming limit switch LS-1 is first engaged

by one of the pair of cartons, no action will take place in the machine until a corresponding carton engages limit switch LS-2 at which time both cartons of the pair are aligned and in engagement with escapement roller 72. Assuming counter reset switch 304 (Fig. 20) is in the "Off" position and pallet "Start" switch 305 is closed, engagement of the pair of cartons with the operating arms of limit switches LS-1 and LS-2 will close normally open contacts 306 and 307 of the respective limit switches and thereby complete a circuit through leads 310 and 310a and normally closed contacts 308 of relay R4 (Fig. 21) and normally closed contacts 309 of relay R1 to coil 311 of the escapement control valve V-1 and thereby shift the valve against the action of spring 302 and supply air pressure through conduit 312 to the head end of air cylinder 81 and retract the piston rod to withdraw escapement roller 72 and permit entry of the pair of cartons into the assembly area of the machine. As striker arm 86 of the escapement device is rotated it momentarily contacts the operating arm of limit switch LS-9 to close, momentarily, the normally open contacts 313 and complete the circuit through coil 314 of counter-operating solenoid 320 if a conventional drum type counter unit C (Fig. 20) in which the drum is notched step by step each time solenoid 320 is energized. Assuming that the machine was shut down with the counter drum arranged to close contacts C20, this shifting of the counter drum one notch or step closes contacts C1 to energize coil 314 of relay R2 to close normally open contacts 315 on that relay and thereby lock in the coil 314 through normally closed contacts 316 of relay R10. Operation of relay R2 also closes normally open contacts 317 and continued rotation of the arm of the entry escapement device actuates limit switch LS-7 to close its normally open contacts 318 and thereby complete the circuit to coil 319 of turning device control valve V-2. This supplies pressure through conduit 321 (Fig. 23) to the rear end of air cylinder 106 to shift arm 96 of the turning device to a position disposed transversely across the belt conveyer 76 as shown in Fig. 10.

When the escapement roller 72 is withdrawn, the pair of cartons is moved by the in-feed belt toward the turning device and one of the cartons contacts the operating arm of limit switch LS-3 closing normally open contacts 322 (Fig. 22) and completing the circuit to energize coil 323 of relay R1. This closes normally open contacts 324 to complete a locking circuit by connector 330 through normally closed contacts 329 of relay R4 and coil 323 of relay R1, and opens normally closed contacts 309 to de-energize coil 311 of escapement control valve solenoid V-1 and thereby release the valve to the action of spring 302 and supply pressure to the rear end of the air cylinder 81 to return the escapement roller to its blocking position disposed in the path of cartons moving along the in-feed conveyer. As the pair of cartons is moved by the in-feed conveyer to the turning device, one of the cartons actuates the arm 119 of limit switch LS-8 to close normally open contacts 325 and complete the circuit energizing coil 326 of the turning device control valve V-2 and thereby shift the valve to supply pressure through conduit 327 to the head end of air cylinder 106, and through valve 121 to the rear end of air cylinder 109 to simultaneously move the arms 96 and 97 of the turning device as a unit about their pivot and turn the pair of cartons through an angle of approximately 90°. This leaves the pair of cartons disposed transversely of the conveyer side by side and moving along the conveyer where they pass under operating arm 300 of limit switch LS-5 to close normally open contacts 327 and energize coil 328 of relay R4. Energization of coil 328 of relay R4 opens normally closed contacts 308 in the circuit of the coil 311 for the escapement control valve V-1 and continues the inoperative condition of that valve until such time as the limit switch LS-5 is released by the passage of the carton along the conveyer whereupon contacts

327 are again open and the coil 328 of the relay R4 de-energized. Energization of relay R4 also opens normally closed contacts 329 to open the holding circuit for the coil 323 of relay R1 and recloses contacts 309 to render operative the circuit to coil 311 of the escapement control valve V-1 so the arrival of another pair of cartons at the escapement will operate the escapement valve.

This first pair of cartons proceeds along the conveyer toward carton stop 170 which is normally disposed in the path of the cartons, the piston rod of air cylinder 181 being extended since spring 331 urges carton stop control valve V-3 to a position supplying air pressure through conduit 332 to the rear end of the air cylinder 181. Once the pair of cartons has cleared the operating arm 300 of limit switch LS-5, the presence of a pair of cartons at the escapement 72 or the arrival of another pair of cartons there to actuate limit switches LS-1 and LS-2 and again close their respective contacts 306 and 307 will energize coil 311 and shift the escapement control valve V-1 to supply air pressure to the head end of the air cylinder 81 and retract the escapement roller. This second pair of cartons then proceeds in the same fashion as the first pair to the turning device which is operated to turn the cartons through an angle of 90° as they are moved by the in-feed conveyer 76 toward the first pair of cartons which are being restrained by the carton stop 170. Operation of the escapement, of course, energizes the counter solenoid 314 to move the counting drum another notch, but since the manipulation of this second pair of cartons is the same as the case of the first pair, the contacts C2 do not change the circuit. This cycle of operation is repeated until the second and third pairs of cartons are aligned behind the first pair and a fourth pair is released by the escapement to move the counting drum and close contacts C4 which are connected by lead 340 to energize coil 333 of relay R5. This energization of relay R5 closes normally-open contacts 334 to energize coil 335 of relay R22 and also close normally-open contacts 336 to initiate operation of timer T1.

Energization of relay R22 closes contacts 337 to complete the circuit into coil 338 of indexing control valve V-7 to supply pressure fluid through conduit 341 to the head end of hydraulic cylinder 239 and thereby move the apron 55 outwardly until the striker 247 contacts the arm of limit switch LS-11A to open contacts 342 and de-energize coil 338. Contacts 343 and limit switch LS-11A are closed in the circuit of coil 344 for relay R6. Opening of contacts 342 also breaks the holding circuit through contacts 337 for coil 335 of relay R22.

As the fourth pair of cartons is pushed beneath the arm 300 of limit switch LS-5, relay R4 is energized and contacts 345 are closed so closure of contacts 343 of limit switch LS-11A causes energization of coil 344 in relay R6 through normally-closed contacts 346 of relay R22 and contacts 334 of relay R5.

Energization of relay R6 closes contacts 347 completing a circuit through closed contacts 348 of relay R5 to coil 349 of carton locator control valve V-8 to supply air pressure through conduit 351 to rear end of air cylinder 281 and thereby shift the carton locator stop plate 284 into position to engage cartons moved onto the apron 55. At the same time coil 352 of carton stop 170 control valve V-3 is energized to shift the valve and supply air pressure through conduit 353 to the head end of the cylinder 181 and retract the stop 170 permitting the conveyer to move the row of pairs of cartons onto that portion of the apron which has been indexed in front of the conveyer. As the last carton clears the arm 300 of limit switch LS-5, contacts 354 are closed to energize coil 355 of pusher control valve V-4 and thereby shift the valve against the action of spring 356 to supply pressure fluid through conduit 357 to the head end of hydraulic cylinder 133 causing movement of the pusher plate 127 toward the cartons moving along the conveyer. When the pusher plate engages the last pair of cartons it pushes the entire row onto the in-

dexed portion of the apron toward the extended carton locator stop 284.

At the time coil 355 of pusher control valve V-4 is energized, coil 356 of relay R23 is also energized closing contacts 357 completing a holding circuit through contacts 358 of relay R6 and normally-closed contacts 359 of relay R8 to cancel out the effectiveness of contacts 354 on limit switch LS-5 during the forward stroke of the pusher plate. This is done because a fifth pair of cartons may be permitted to enter the escapement and contact limit switch LS-5 prior to the completion of the stroke of the pusher plate, in which case the opening of contacts 354 on limit switch LS-5 would de-energize the coil 356 and cause a reversal of the pusher plate before it completed the transfer operation.

When the leading carton contacts the extended carton stop 284 it closes contacts 361 of limit switch LS-6 to energize coil 362 of relay R8 and simultaneously energize coils 363 and 364 of the carton locator stop control valves V-8 and V-9 to retract both of the stops 283 and 284.

Energization of coil 362 in relay R8 opens contacts 359 to break the holding circuit for coil 344 of relay R6, inasmuch as energization of the coil 344 opened normally-closed contacts 365. This in turn de-energizes coil 352 of the carton stop control valve V-3 permitting spring 331 to reverse the valve so air pressure is supplied through conduit 332 to the rear end of the cylinder 181 to project the carton stop 170 into the path of the conveyer. Also, coil 355 of the pusher control valve V-5 is deenergized so spring 356 reverses that valve and supplies pressure fluid through conduit 366 to the rear end of hydraulic cylinder 131 and retracts the pusher plate 127 to its original position. Thus, all parts of the transfer mechanism are returned to their normal position to await the arrival of additional cartons.

As the fifth pair of cartons arrive at the escapement to operate limit switches LS-1 and LS-2, the sequence of operation continues as before, except that this pair of cartons is not turned. When the escapement 72 is actuated by the arrival of the fifth pair of cartons, the operation of limit switch LS-9 to shift the counter drum closes contacts C5 to energize coil 367 of relay R10 and thereby opens contacts 316 and breaks the holding circuit for relay R2, so contacts 317 are again opened and the turning device 60 rendered inoperative. Energization of relay R10 also closes contacts 360 to energize coil 326 of the turning control valve V-2 and ensure that arm 96 is retracted. Hence, the fifth pair of cartons passes the turning device in a straight line and blocks release of the escapement until these cartons pass limit switch LS-5. This fifth pair of cartons continues until it engages carton stop 170 and the sixth pair of cartons proceeds in the same manner, the shifting of the counter drum to close contacts C6 having no effect on the operation. Inasmuch as only three pairs of cartons arranged longitudinally are accumulated in a row, the passage of the seventh pair of cartons through the escapement actuates limit switch LS-9 to move the counter drum and close contacts C7 which is connected by lead 370 to energize coil 368 of relay R11 closing contacts 369 to actuate timer T1 and closing contacts 371 to energize coil 335 of relay R22 and thereby energize coil 338 of indexing control valve V-7 to cause the apron to again index until it comes to rest in contact with limit switch LS-11b opening contacts 372 to break the circuit to the coil 338.

The purpose of timer T1 is to hold closed contacts 374 until such time as the apron has moved away from limit switch LS-11a and then to isolate the coil 335 of relay R22 from the contacts 371 of initiating relay R11, so that the contacts 371 of relay R11 will not cause continuation of the stroking of the apron beyond the position of limit switch LS-10.

When the apron has indexed and limit switch LS-11b is actuated, contacts 375 are closed to close the circuit to coil 344 of relay R6 and energize coil 352 of carton stop

control valve V-3, thereby retracting the carton stop and also energizing coil 355 of pusher control valve V-4 to initiate the forward movement of the pusher plate 127. In the meantime, energization of coil 344 of relay R6 closes contacts 347 to complete the circuit through contacts 377 of relay R11 to energize coil 378 of carton locator stop control valve V-9 and thereby supply air pressure to the rear end of air cylinder 282 and move carton locator stop 283 outwardly to its projected position for engaging the leading carton in the row being moved by the pusher plate onto the apron. When the leading carton engages the stop 283, it actuates limit switch LS-6 to close contacts 361 and energize the coil 362 of relay R8 thereby causing return of all of the transfer devices to their normal positions as heretofore described.

The eighth and ninth pairs of cartons enter the pallet loading machine through the escapement just as the fifth and sixth pairs of cartons entered the escapement, and upon entry of the tenth pair of cartons the counter drum closes contacts C10 which energize coil 368 of relay R11 to index the apron to its final position where it actuates limit switch LS-11c to open contacts 381 and close contacts 382. In this position the apron also contacts limit switch LS-10 to close contacts 383 so when the last row 20 of cartons is moved onto the apron and limit switch LS-6 is moved by engagement with the carton locator stop 283 energization of coil 362 and relay R8 closes contacts 384 to complete the circuit through coil 385 of relay R19. In this way contacts 386 are closed to complete a locking circuit through normally-closed contacts 387 of limit switch LS-11 and normally-closed contacts 388 of relay R9 to energize coil 389 of the apron control valve V-7. This shifts the valve to supply pressure fluid through conduit 390 to the rear end of hydraulic cylinder 239 and extend the piston rod and withdraw the apron thereby pulling the cartons in the last row against the stripper beam 289 to strip the cartons off of the apron as it is retracted to its position above the empty pallet magazine. In this operation the layer of cartons upon the apron is deposited on the pallet which is supported on the full pallet lift platform 53. Since the empty pallet is in engagement with finger roller 251 of full pallet lift control 246, the empty pallet is disposed immediately beneath the apron so that cartons drop only a very short distance from the apron onto the pallet.

Before the apron retracts, the energization of the coil 385 of relay R19 and the closure of contacts 386 also energizes coil 391 of the closing-in guide control valve V-10 to shift the valve against the action of spring 392 and cause air pressure to be supplied through conduit 393 to the head ends of the air cylinders 293 and 294, for the purpose of withdrawing the closing-in guides 70 and 71 and permitting the layer of cartons to drop from the apron onto the empty pallet on the lift 53. When the apron has been withdrawn to its retracted position it engages limit switch LS-11 to open contacts 387 which de-energizes the coil 389 of the valve V-7 and also breaks the holding circuit for coil 385 of relay R19. This causes de-energization of coil 391 on the control valve V-10 for the closing-in guides and releases the valve to the action of spring 392 so air pressure is supplied through conduit 395 to the rear ends of the air cylinders 293 and 294, for the purpose of moving the closing-in guides into engagement with the sides of the cartons in the layer deposited on the pallet.

At the same time that limit switch LS-6 is actuated to energize the coil of relay R8 the coils 363 and 364 of the carton locator stop control valves V-8 and V-9 are energized to retract the stops in a manner previously described. Likewise, all of the transfer mechanisms are restored to their original and normal positions so the machine is ready to receive and assemble cartons into another layer.

At the time that the apron is retracted, the lift control arm 246 is extending over the pallet and control roller

257 on the arm is engaged by the pallet. In this situation, contacts 393 on limit switch LS-26 are open and contacts 396 on limit switch LS-26 are closed. As limit switch LS-25 is actuated, its normally closed contacts 397 are open. When the apron is retracted the control arm 246 is engaged by the control arm cam striker 245 and withdrawn, thereby actuating limit switch LS-26 to close normally open contacts 393 and open normally closed contacts 396. Closure of contacts 393 energizes coil 398 of relay R7 to close contacts 399 and thereby complete the circuit through normally closed contacts 401 of relay R12 and 402 of limit switch LS-27, which is a safety switch responsive to slack in the chain 220, to energize coil 403 of the full lift control valve V-6 thereby shifting the valve to supply pressure fluid through conduit 404 to the head end of hydraulic cylinder 214, moving the piston in the cylinder to cause the platform of the full pallet lift to drop with the cartons deposited on it.

As the apron completes its withdrawal, the striker 245 passes the cam roller 272 and releases the arm 246 to the action of dashpot control 258. At this point the sensing roller 257 engages the sides of cartons on the pallet so the pallet lift continues to lower the pallet with the cartons on it. When the upper surface of the cartons in the layer on the pallet reach a point below the sensing roller 257 on the control arm 246 the control arm under the influence of dashpot 258 moves outwardly to overlie the cartons on the pallet. This action controls limit switch LS-26 to open contacts 393 de-energize coil 403 in the full lift pallet control valve V-6. The valve then returns to its neutral position and, inasmuch as contacts 396 of limit switch LS-26 are returned to their normally closed position, the circuit for energizing coil 406 of relay R9 is completed and contacts 407 on relay R9 are closed. Since contacts 408 on relay R20 and 409 on relay R12 are normally closed, the circuit to coil 411 of full lift control valve V-6 is closed and the coil is energized to shift the valve in the opposite direction causing pressure fluid to flow through conduit 412 to the rear end of the hydraulic cylinder 214 and move the piston in the cylinder in a direction to raise the full pallet lift. Upward movement of the lift continues until the top surface of the cartons engages sensing roller 257 and moves the finger about its horizontal pivot until limit switch LS-25 is actuated and its contacts 397 are opened to deenergize coil 406 of relay R9 and thereby open contacts 407 and de-energize coil 411 in the full pallet lift control valve V-6. This locks the hydraulic circuit with the cartons in position immediately below the control arm and, if the lift drops by reason of leakage in the system the contacts 397 of limit switch LS-25 will immediately be closed and the up circuit for the full pallet lift actuated as previously explained, so the lift is at all times maintained with the top surfaces of the cartons immediately beneath the control arm and the apron.

While the full pallet lift has been lowering the layer of cartons beneath the level of the apron and raising them into contact with the sensing roller of the control arm the formation of another layer on the apron may be started. Thus, with the eleventh pair of cartons at the escapement, limit switches LS-1 and LS-2 are actuated to operate the escapement which in turn actuates limit switch LS-9 to operate the counter solenoid and shift the counter drum a notch to close contacts C11. Inasmuch as the second layer on the pallet is to follow the pattern of cartons as illustrated in Figure 1, the first six pairs of cartons fed into the second layer will not be turned, but will be arranged in four parallel rows on the front of the apron with the last four cartons of the layer turned. As the assembly of the eleventh, twelfth and thirteenth pair of cartons is to follow exactly the pattern of the fifth, sixth and seventh pair of the eighth, ninth and tenth pair of cartons contacts C11 do not change the electrical control circuit in any way so the turning device is not operated and the eleventh pair of cartons moves to the carton stop.

63 where it is followed by the twelfth pair and the thirteenth pair. When the thirteenth pair enters the escapement, contacts C13 of the counter are closed to energize coil 368 of relay R11 closing contacts 369 to energize timer T1 and contacts 371 to energize coil 335 of relay R22 thereby indexing the carriage until limit switch LS-11A is actuated to open the indexing circuit and simultaneously energize relay R6 to withdraw the carton stop 63, operate the pusher plate 127, and project carton locator stop 233 into the path of the row of cartons as is moved by the conveyer and the pusher plate onto the apron. Likewise the assembly of the fourteenth, fifteenth and sixteenth pair of cartons into a row closes contact C16 of the counter and causes the transfer of this row 15 of pairs of cartons onto the apron which has been indexed to its second step.

Inasmuch as the seventeenth pair of cartons is to be turned transversely of its direction of travel, the operation of the escapement in response to the arrival of this pair 20 of cartons rotates the counter drum to close contacts C17 and again energize coil 314 of relay R2 which conditions the turning unit assembly for operation when contacts 318 are closed by operation of limit switch LS-7 to energize coil 319 in turning device valve 302 to supply air pressure 25 through conduit 321 to the rear end of air cylinder 106 and shift the right hand arm 96 of the turning device into the path of the cartons so subsequent operation of LS-8 when the cartons arrive at the turning device causes the arms 96 and 97 to turn as a unit by energizing coil 326 30 of the turning control valve V-2 and shifting the valve to supply air pressure to the head end of cylinder 106 and the rear end of cylinder 109. This pair of turned cartons continues until it reaches the carton stop 63. The eighteenth pair is treated in like fashion and is moved 35 into position immediately behind the seventeenth pair.

When the nineteenth pair of cartons passes the escapement the counter closes contacts C19 which do not effect the manipulation of this pair of cartons but do energize coil 412 of relay R14, thereby closing contacts 413 of 40 the holding circuit for relay R14 and also closing contacts 414 in the circuit for contacts C20. Contacts 414 of relay R14 are maintained closed during continuous operation of the machine except when the counter is reset by shifting switch 304 to its "On" position. The 45 resetting of the counter moves the drum to close contacts C20 and it is not desired that the operation for contact C20 be carried out at that time hence, the operation of the counter reset switch 304 breaks the holding circuit for relay R14 and opens contacts 414. Once the counter 50 is reset, the completion of a cycle operation again energizes relay R14 and its holding contacts 413 are maintained closed for cycle after cycle of operation until the reset switch is again moved from its "Off" position.

The final pair of cartons to be assembled in this layer 55 is the twentieth pair which, upon reaching the escapement and causing operation of the counter drum to close contacts C20 and energize coil 333 of relay R5 so contacts 334 and 336 of relay R5 are closed to energize the coil of relay R22 and the timer T1. This causes energization 60 of the coil 338 of the indexing control valve V-7 so the apron is indexed to its outermost position where it engages limit switch LS-11C as well as limit switch LS-10. When the row of turned cartons engages the carton locator stop which has been extended, limit switch LS-6 is actuated to close its contacts 361 and energize coil 362 of relay R8 that completes a locking circuit through its own contacts 380 and contacts 390 on relay R5. This energization of relay R8 operates as previously described 65 to return the transfer mechanisms to their normal positions and also, since limit switch LS-10 has its contacts 383 closed, completes through contacts 384 the circuit to coil 385 of relay R19 to close contacts 386 and energize coil 389 of the apron control valve V-7, causing actuation of the hydraulic cylinder 239 to withdraw the 70 apron. Simultaneously coil 391 of the closing-in guard 75

control valve V-10 is energized to cause retraction of the closing-in guards while the cartons are dropping onto the layer of cartons supported by the pallet immediately beneath the apron.

As the apron withdraws it of course has its striker engage the cam on the control arm to retract the control arm and close contacts 393 of limit switch LS-26 while opening contacts 396 of that limit switch to initiate through energization of coil 398 of relay R7 and closure of contacts 399 the energization of coil 403 in the full lift control valve V-6 to supply fluid pressure to the hydraulic cylinder 214 and cause downward movement of the platform, the pallet and the layer of cartons thereon. This downward movement of course continues until the sensing roller passes over the top of the cartons so the arm again operates limit switch LS-26 to open contacts 393 and close contacts 396. As the control finger is then depending from the control arm, limit switch LS-25 has its contacts 397 closed to complete the circuit through coil 406 of relay R9 causing energization of coil 411 to reverse the position of the full lift control valve V-6 thereby causing upward movement of the lift until the top surface of the top layer of cartons on the lifting platform engages the sensing roller and shifts it about its horizontal axis to actuate limit switch LS-25 and open contacts 397.

At this point the machine has completed the formation of layers of cartons into two layers of interlocking patterns and is ready to receive another layer of a pattern corresponding to the layer first deposited upon the pallet so the machine is again ready to start another complete cycle of the counter and entry of another pair of cartons will operate the counter to close contacts C1 and complete the formation of additional layers of alternating patterns until the desired number of layers have been piled on the pallet.

The number of tiers or layers to be accumulated on the pallet is determined by a tier selector switch 420 which may be positioned so either limit switch LS-17 or limit switch LS-18 is effective to discontinue the stacking operation and cause lowering of the full pallet lift to the bottom of the shaft. Assuming the tier selector is set as shown in Fig. 22 so limit switch LS-18 is effective to accumulate a larger number of layers on the pallet, actuation of the limit switch LS-18 upon lowering of the full pallet lift to a predetermined level closes normally opened contacts 422 to energize coil 423 of relay R20. A holding circuit for relay R20 is completed by closing normally opened contacts 424 through normally closed contacts 425 of limit switch LS-16. Energization of coil 423 of relay R20 also closes normally opened contacts 426 and opens normally closed contacts 408 to energize coil 403 of the full pallet lift control valve V-6 thereby supplying pressure through conduit 404 to the head end of cylinder 214 and continuing the lowering of the full pallet lift until the full pallet lift reaches the bottom of the shaft and limit switch LS-21 is actuated. Actuation of the limit switch LS-21 closes normally opened contacts 421 of limit switch LS-21 to complete a circuit through normally closed contacts 408 of relay R13 and contacts 429 of relay R20 to energize coil 431 of relay R12 which opens contacts 401 of relay R12 and de-energizes the coil 403 of full pallet lift control valve V-6. Closure of limit switch LS-21 is also effective through contacts 434 of relay R13 and normally closed contacts 461 of limit switch LS-20 to energize coil 435 of the motor 440 (Fig. 4) which drives the empty pallet transfer chain 153 and the full pallet discharge chain conveyor 155. The full pallet lift is thereby discharged onto the conveyor 57. At the same time, an empty pallet is transferred by the transfer conveyor 53 from the empty pallet magazine onto the full pallet lift. Release of the bar 164 upon transfer of the empty pallet onto the full pallet lift causes shaft 162 to turn under the action of spring 165 thereby caus-

ing striker 169 to actuate limit switch LS-16 opening normally closed contacts 425 in the holding circuit for coil 423 of relay R20 so that relay is de-energized and contacts 408 are returned to their normally closed position to close the circuit to coil 411 of the full pallet lift control V-6 and cause pressure fluid introduced through conduit 412 to the rear end of the cylinder 214 to raise the lift until it engages the finger roller of the control arm where its upward movement is arrested with the empty pallet disposed immediately beneath the level of the apron.

When the empty pallet leaves the empty pallet magazine it releases the bar 164 so limit switch LS-13 is released and its contacts 437 are returned to their closed position. When the empty pallet lift platform 185 is in its lowered position, a striker on torque rod 191 operates limit switch LS-14 so its contacts 438 are closed and the circuit is completed to coil 439 of the empty pallet lift control valve V-5, shifting the valve to supply air pressure through conduit 441 to the rear end of air cylinder 186 and cause upward movement of the empty pallet lift. As the torque rod is rotated, limit switch LS-14 is released, but since the valve V-5 is a momentary contact 2-position valve it remains in position and air pressure continues to be supplied to the rear end of the air cylinder and completes the stroke of the piston to raise the empty lift platform.

When the platform contacts the bottom pallet in the stack of pallets in the empty pallet magazine it lifts the whole stack and at the same time by operation of the cam rollers 207 causes retraction of the empty pallet support fingers 203 so the entire stack of empty pallets is supported on the lift. At the time of the stroke, the torque rod contacts limit switch LS-15 closing its contacts 443. If these are pallets in the empty pallet magazine their presence actuates striker 451 (Fig. 4) and limit switch LS-12 to close contacts 444 so the circuit through coil 445 of the empty pallet lift control valve V-5 is energized to shift the valve and supply air pressure through conduit 446 to the head end of the air cylinder 186 and cause the lowering of the empty pallet lift. During the first portion of the down stroke of the lift platform, the stack of pallets is supported on the platform until the opening in the side of the second pallet from the bottom is opposite the pallet support fingers 203. At this point the cam operating rollers 207 attached to the lift platform contact the support finger drive cam 204 on the bottom side of centre and force the empty pallet lift fingers 203 to enter the magazine and engage the next to the bottom pallet thereby supporting the entire stack of pallets, while the platform and a single pallet continue downwardly. When the empty pallet lift platform arrives at its lowermost position with an empty pallet thereon it engages limit switch actuating bar 168 to actuate limit switch LS-13 and open its normally closed contacts 437 and again close its contacts 432 so the conveyor discharge chain circuit is conditioned for operation. The pallet then rests upon the transfer chain while the empty pallet lift platform continues to the bottom of the stroke where the torque rod 191 actuates limit switch LS-14 to close contacts 438 but upward movement of the empty pallet lift platform is of course prevented as long as contacts 437 on limit switch LS-13 are open.

When loading of another pallet on the full pallet lift has been completed, that lift is lowered, the full pallet discharged and another empty pallet transferred to the full pallet lift, the entire cycle repeating itself as just described.

Several safety factors are incorporated in the control circuits, such as, for example, emergency stop buttons 451, 452 and 453 which are strategically located at points of the machine so the entire apparatus can be brought to a standstill by touching any of these stop buttons in the event there is any fault in the pallet loading operation,

The machine is conditioned for operation by pressing start button 454 which closes the circuit from transformer 477 to energize starter coil 455 for the oil pump. This coil is locked in by closure of its contacts 456. Likewise, as long as sufficient air pressure is maintained in the air system, contacts 457 of an air pressure switch 458 will be closed and power will be properly supplied by common leads 484 and 485 to the control circuits. Belt conveyer motor 478 (Fig. 1) is continually driven by energization of coil 459 controlling the starter for that motor.

In the event an empty pallet is not in the transfer position at the bottom of the empty pallet magazine and resting on actuator bar 168 to close limit switch LS-13, relay R13 is not energized, so the discharge conveyer chain is not actuated when the full pallet lift platform reaches its lowermost position, and limit switch LS-21 is closed because contacts 434 on relay R13 remain open. Under these conditions, and to avoid heating in the hydraulic system, contacts 428 of relay R13 remain closed and contacts 429 on relay R20 are closed due to the energization of that relay, so coil 431 of relay R12 is energized when the full pallet lift arrives at its lowermost position. This opens contacts 401 and 409 of relay R12 in the circuits for coils 403 and 411 of the full pallet lift control valve V-6 so the valve moves to its neutral position.

When the apron is in its extended position and it is ready to be withdrawn, before an empty pallet or a layer of cartons is in position to receive the layer to be discharged from the apron, limit switch LS-25 is in its normal position since sensing roller 257 is lowered and contacts 397 of limit switch LS-25 are open so coil 406 of relay R9 is de-energized and contacts 388, connected by lead 483 to contacts 387 of limit switch LS-11 and by lead 484 to coil 391 of valve V-10, are open to prevent operation of the apron control valve V-7 for the withdrawal stroke of the apron.

Should a row of articles be arranged in the assembly area for transfer onto the apron before an assembled layer has been lowered sufficiently to permit an indexing stroke of the apron, the cartons obstructing indexing movement of the aprons engage rollers 257 and prevent the control arm from swinging outwardly, so limit switch LS-26 is closed and coil 398 of relay R7 is energized thereby opening contacts 475, which are connected by lead 481 to normally closed contacts 466 of relay R21 and by lead 482 to coils 333 and 368 of relays R5 and R11, for preventing operation of the transfer mechanisms or indexing of the apron. When coil 385 is energized by operation of limit switch LS-19 to close contacts 386 and effect the withdrawal stroke of the apron by energizing coil 389 of apron control valve V-7, normally opened contacts 462 of relay R19 are closed thereby energizing coil 463 of relay R21. This closes contacts 464 of relay R21 through a holding circuit to maintain relay R21 energized and contacts 466 open until another carton passes limit switch LS-5 to close its contacts 327 and energize coil 328 of relay R4 thereby opening contacts 365 of relay R4 and breaking the holding circuit for the coil 463 of relay R21, permitting contacts 466 on relay R21 to close so the coils of relays R5 and R11 are conditioned for operation.

In case a row of cartons is ready for transfer onto the apron before the withdrawal stroke of the apron is completed, coil 385 of relay R19 is energized, so its contacts 419 are opened and operation of the transfer mechanism is prevented until the withdrawal of apron is completed to actuate limit switch LS-11 and open its contacts 387 thereby de-energizing coil 385 of relay R19 and returning contacts 419 to their normally closed position.

Upon dropping of a loaded pallet to its discharge position, when an empty pallet is not in transfer position in the empty pallet magazine, the actuator bar will not be depressed and the contacts 432 of limit switch LS-13

will not be closed so coil 433 of relay R13 will not be energized and the discharge conveyer motor will not be started. In the event a loaded pallet is in position on the discharge roller conveyer so another loaded pallet cannot be so discharged, the normally closed contacts 461 of limit switch LS-20 will be opened, thereby preventing operation of the starter for the discharge conveyer.

If there is any difficulty in the assembly of cartons on the apron, it may be indexed manually by depressing push button 467 to complete the energization of coil 335 and relay R22 and effect indexing of the apron in the manner already described in connection with the automatic operation. Similarly, manual actuation of the pusher may be effected by depressing push button 468 to complete the circuit to coil 355 of pusher control valve V-4.

When it is desired to clear the machine, the apron may be withdrawn manually by depressing push button 469 to complete the circuit through coil 389 of the apron control valve V-7. After the apron is manually withdrawn, the transfer mechanism will not be reset, particularly if the pusher plate is first manually moved to clear the pattern build up area. In order to insure return of the transfer mechanism, coil 362 of relay R8 is energized upon depression of push button 469 because this also energizes coil 385 of relay R19 and closes its contacts 471 in the circuit of coil 362 for relay R8. Thus, the relay R8, which controls the return of the transfer mechanisms and is normally actuated by closure of limit switch LS-6, is in this instance actuated by closure of contacts 471 of relay R19. The holding circuit for relay R8 as determined by its contacts 380 may be broken by opening contacts 390 of relay R5 or contacts 472 of relay R11.

At any time the full pallet lift platform may be lowered to its discharge position by manual operation of lift discharge switch 486 to energize coil 423 of relay R20.

What is claimed is:

1. A pallet loading machine comprising a frame defining a lift shaft, a lift for raising and lowering a pallet within said shaft, an apron slideably mounted in said frame at the upper end of said shaft for movement between an extended position overlying a pallet on said lift and a retracted position withdrawn from said shaft, means for feeding articles to a location adjacent one side of said shaft at the upper end thereof, releasable stop means normally operable to accumulate articles on said feeding means at said location in a row extending in a direction normal to the direction of movement of said apron, means responsive to the accumulation of a predetermined number of articles in the row for releasing said stop means and transferring the accumulated row from said feeding means onto said apron, and indexing means responsive to the location of the accumulated row of articles upon said apron for restoring said stop means to its article accumulating condition and indexing said apron toward said extended position to position said apron to receive a subsequent row of articles from said accumulating means.
2. A pallet loading machine comprising a frame defining a lift shaft, a lift for raising and lowering a pallet within said shaft, an apron slideably mounted within said frame at the upper end of said shaft for movement between an extended position overlying a pallet on said lift and a retracted position withdrawn from said shaft, feeding means for transferring articles in line to a location adjacent the upper end of said shaft, releasable stop means normally positioned to accumulate articles on said feeding means at said location in a row extending in a direction normal to the direction of movement of said apron, means responsive to the accumulation of a predetermined number of articles in the row for successively releasing said stop means, transferring the accumulated row from said feeding means onto said apron, and restoring said stop means to its article accumulating position, indexing means

operable between successive operations of transfer means for moving said apron successive increments toward its extended position to locate successive rows of articles transferred to said apron in side-by-side relationship, means responsive to the arrival of said apron at said extended position for driving said apron to said retracted position to deposit articles supported upon said apron onto said pallet in a layer of rows of articles in side-by-side relationship, means operable upon the retraction of said apron for lowering said lift until said layer of articles is located below said apron, and means responsive to the arrival of said articles in the last mentioned position for indexing said apron from said retracted position toward said extended position to receive an additional row of articles from said accumulating means.

3. A pallet loading machine comprising a conveyer for feeding articles in a first direction to a discharge end, a retractable stop located at the discharge end of said conveyer and normally positioned to accumulate articles on said conveyer in a row extending in said first direction, an apron mounted beyond said discharge end of said conveyer for movement in a direction normal to said first direction, a pusher mounted adjacent said conveyer for movement in forward and return strokes parallel to said first direction between a normal retracted position above said conveyer upstream from said discharge end and an actuated position overlying said apron, means responsive to the accumulation on said conveyer of a predetermined number of articles in the row for retracting said stop, positioning said pusher in engagement with the last accumulated article and driving said pusher to said actuated position to thereby transfer the accumulated row of articles from said conveyer to said apron, and means responsive to the location of said row of articles on said apron for returning said stop to said normal position, indexing said apron to move said row of articles out of alignment with said conveyer and returning said pusher to said retracted position.

4. A pallet loading machine as defined in claim 3 wherein said pusher includes an article engaging member, a support member movable between said retracted and said actuated positions, means mounting said article engaging member upon said support member for pivotal movement about a horizontal axis between an elevated position wherein said article engaging member is located clear of the path of articles on said conveyer and a lower position wherein said article engaging member is located in the path of articles on said conveyer, and means for maintaining said article engaging member in said elevated position during movement of said support member from said actuated position to said retracted position and during the initial portion of movement of said support member from said retracted position toward said actuated position.

5. A pallet loading machine comprising a conveyer having releasable means for accumulating articles in a row upon said conveyer at the discharge end thereof, a stationary bar projecting beyond the discharge end of said conveyer in general alignment with one longitudinal side of a row of articles accumulated on said conveyer, a rectangular apron supported upon said frame means for movement beneath said bar transversely of said conveyer between a retracted position wherein said one edge of said apron is located in substantial vertical alignment with said bar and an extended position wherein the opposite edge of said apron is located in substantial vertical alignment with said bar, transfer means at the discharge end of said conveyer actuatable to transfer an accumulated

row of articles from said conveyer onto said apron by pushing the accumulated row longitudinally along said bar, means responsive to the accumulation of a pre-selected number of articles in a row upon said conveyer for releasing said accumulating means and actuating said transfer means, means responsive to the arrival of the row of articles upon said apron for restoring said accumulating means to its article accumulating condition and indexing said apron toward said extended position to shift the transferred row of articles transversely away from said bar a distance sufficient to permit a subsequent row of articles to be transferred onto said apron at a location between said bar and the first mentioned row of articles.

15. 6. A pallet loading machine as defined in claim 5 including lift means for supporting a pallet below the extended position of said apron, and means responsive to the accumulation of a pre-selected number of rows of articles upon said apron for driving said apron to said retracted position whereby articles are stripped from said apron by said bar onto said pallet.

25. 7. A pallet loading machine comprising a frame defining a lift shaft, a lift for raising and lowering a pallet within said shaft, an apron slideably mounted in said frame at the upper end of said shaft for movement between an extended position overlying a pallet on said lift and a retracted position withdrawn from said shaft at one side thereof, means for feeding articles to a location at a side of said shaft adjacent said one side of said shaft at the upper end thereof, releasable means for accumulating articles on said feeding means at said location in a row extending from said shaft in a direction normal to the direction of movement of said apron, means responsive to the accumulation of a row consisting of a predetermined number of articles for releasing the accumulating means, driving the accumulated row from said feeding means onto said apron, and restoring the accumulating means to its articles accumulating condition, and indexing means responsive to the location of the accumulated row of articles upon said apron in alignment with said feeding means for driving said apron a predetermined distance toward said extended position to locate said apron in a position to receive a subsequent row of articles, means responsive to the location of a selected number of rows of articles on said apron for driving said apron to said retracted position, and means extending across said one side of said shaft above said apron for stripping the articles from said apron to said pallet during movement of said apron to said retracted position.
